UNITED STATES PATENT OFFICE.

ALEXANDER W. MARR, OF CANTON, OHIO.

TIRE-SAVING JACK.

1,257,509.

Specification of Letters Patent. Patented Feb. 26, 1918.

Application filed August 10, 1917. Serial No. 185,587.

To all whom it may concern:

Be it known that I, ALEXANDER W. MARR, a citizen of the United States, and a resident of the city of Canton, in the county 5 of Stark and State of Ohio, have invented certain new and useful Improvements in Tire-Saving Jacks, of which the following is a specification.

This invention relates to new and useful 10 improvements in tire-saving jacks.

The principal object of my invention is to provide a simple, inexpensive and efficient jack-set for the purpose of relieving the tires of an automobile or other vehicle from 15 the weight of the body when the latter is not in use. Another object of the invention is to provide a toggle-lever operating mechanism which is readily detachable from the jack proper, so that one operating lever may 20 be easily applied to each of four jacks, one for each wheel of an automobile, thereby reducing the cost of the set very materially.

Other important and incidental objects will be set forth in the following specification and particularly pointed out in the subjoined claims.

The preferred form of embodiment of my invention is illustrated in the accompanying drawings, of which Figure 1 is a 30 side elevational view of my improved jack, with the toggle-lever applied thereto in position to raise the lifting bar. Fig. 2 is a side view of the upper portion of the jack, showing the position of the toggle-lever 35 after the lifting bar has been raised. Fig. 3 is a side view of the pawl holding the lifting bar in its elevated position. Fig. 4 is a side view of said pawl in the position it occupies before the lifting bar has been 40 raised. Fig. 5 is a top plan view of the jack, with the lever mechanism removed. Fig. 6 is a front view of the standard, showing the slot provided therein for the lifting bar guiding screw. And Fig. 7 is a plan view of the toggle-lever.

Throughout the specification and drawings, similar reference characters denote corresponding parts.

In a detailed description of the preferred 50 form of embodiment of my invention, the numeral 1 designates a standard mounted upon a base 2. The standard 1 is tubular to receive for a vertical movement therein, a

lifting bar 3 to the top of which a concaved head 4 is pivoted for a horizontal 55 turning movement thereon. In order to prevent the lifting bar 3, which is preferably circular in cross section, from turning within the standard 1, the latter contains a front vertical slot 5 that loosely 60 receives a guide screw 6 secured to the lower end of said lifting bar. (See Fig. 6.)

Fixedly secured to the upper end of the lifting bar 3 a short distance below its head 4, is a collar 7 which consists of a metallic band that does not completely surround the bar 3 but whose ends extend outwardly from a place in its periphery in the form of two projecting ears 8 8. Extending between these ears 8 8 is a bolt 9 which 70 is tightly secured thereto by means of a nut 10. The bolt 9 loosely passes through the upper end of a downwardly pointed pawl 11 so constructed and positioned between the ears 8 8 that, when the lifting bar 75 3 has been raised to the position shown in Fig. 3, the nose portion 12 of the pawl will fall by gravity above the top edge of the standard 1, to hold the bar in its elevated position, and so firmly that it cannot be 80 jarred loose as in many other jacks. To permit the bar 3 to be lowered, the nose portion 12 of said pawl must be withdrawn from engagement with the top edge of the standard 1, whereupon said bar will drop 85 down into the standard.

For the purpose of easily raising and lowering the bar 3 after its head 4 has been placed under a load, the following described lever mechanism is provided. Referring 90 to Figs. 1, 2 and 7, the numerals 13 13 designate a pair of similar fulcrum arms. Each arm 13 has near its inner end a downwardly extending boss 14, while in the forward end of each a notch 15 is provided. The 95 arms 13 13 are firmly connected together by a cross piece 16 extending between their bosses 14 14, to form a yoke piece which loosely straddles the standard 1 so that their notches 15 may receive a fulcruming 100 pin 17 extending outwardly from each side of the upper middle portion of said standard.

The inner end of each of the arms 13 13 is pivotally connected to a curved engaging member 18. These members 18 18,

which are preferably claw-shaped flat metallic pieces, are firmly connected together at their inner ends by cross elements 19 and 20, to the middle portions of which one end of a lever 21 is fixedly secured. (See Figs. 1, 2 and 7.)

Formed in the outer claw ends of each of the members 18 18 is a notch 22 adapted to receive a pin 23 projecting outwardly from each side of the collar 7 on the upper end of the lifting bar 3. When the lever 21 is raised to the position shown in Fig. 1, the notched ends 22 of the members 18 18 are adapted to engage the pins 23 23 for the purpose of raising the lifting bar 3 after the fulcrum arms 13 13 have been applied to the jack frame as follows.

The standard 1 is first positioned so that its head 4 will come under the axle of an automobile or other load to be raised. The lever mechanism is then applied to the standard 1 so that the notched ends of the fulcrum arms 13 13 will fit over the pins 17 17 thereon. The lever 21 is then raised to bring the notched ends of the members 18 18 into engagement with the pins 23 23 that project outwardly from the collar 7 on the lifting bar 3. Force is now applied to the outer end of the lever 21 whereupon, with the pins 17 17 as fulcruming means, the inner ends of the arms 13 13 will be moved toward the standard and the notched ends of the members 18 18 upwardly, carrying with them the lifting bar 3 through engagement with the pins 23 23 on its collar 7.

When the lifting bar 3 has been raised to the position shown in Figs. 2 and 3, the nose portion 12 of the pawl 11 will have been moved, by gravity, upon the top edge of the standard 1 to maintain the lifting bar 3 and its load in its raised position. The lever mechanism may then be withdrawn and applied to a standard 1 beneath another automobile wheel, or any other load to be raised, and so on until all the standards positioned for use have been operated. One lever mechanism will thus suffice for any number of standards which it may be desired to use in a garage, for instance, to jack up the wheels 50 of automobiles for the purpose of saving their tires. My improved jack may also be used with economy and efficiency for other load raising purposes.

When it is desired to lower a load already raised, the lever mechanism is applied to the standard in the manner before described and the lifting bar 3 raised thereby sufficiently to enable the nose portion of the pawl 11 to be withdrawn from the top edge of the standard 60 and, whereupon the load will descend as the outer end of the lever 21 is permitted to rise.

There is provided in the outer end of the lever 21, a square hole 24 which is adapted to receive the nut 10 for the purpose of vertically adjusting the collar 7 on the stand-

ard 3, whereby the jack will accommodate automobiles and other vehicles of different heights.

It will now be seen that I have provided a simple, inexpensive and efficient tire-saving 70 jack, and that one lever mechanism will suffice for a set of two or more standards. The last named feature particularly adapts my improved jack for automobile tire-saving use. 75

I do not wish to be limited to the details of construction and arrangement herein shown and described, and any changes or modifications may be made therein within the scope of the subjoined claims. 80

Having described my invention, I claim:

1. In a jack, the combination with a tubular standard, of a lifting bar slidably movable therein, a pin projecting outwardly from opposite sides of the upper portion of the lifting bar, a lever, a pair of prong members fixedly secured to the inner end of said lever, and having notched ends for removable engagement with the projection on the lifting bar, a pin projecting outwardly 90 from opposite sides of said standard, and a yoke piece pivotally secured to the prong members, said yoke piece having notched free ends adapted to straddle the standard to removably receive the projecting pins 95 thereon, whereby the lifting bar may be raised when the outer end of the lever is depressed.

2. In a jack, the combination with a tubular standard, of a lifting bar slidably movable therein, a collar secured to the upper end thereof, a pin projecting outwardly from opposite sides of said collar, a lever, a pair of claw-shaped prong members carried by the inner end of said lever, each claw-shaped 105 member having a notched end for removably engaging one of the collar pins, a pin projecting outwardly from opposite sides of said standard, and a pair of fulcruming arms firmly connected together at their inner ends, each of said arms being pivotally secured to the middle portion of a respective prong member, and having a notched outer end for removable engagement with one of the pins projecting outwardly from 110 said standard.

3. In a jack, the combination with a tubular standard, of a lifting bar slidably movable therein, a lever for raising said lifting bar, a pawl pivoted to said lifting bar above the standard, and a downwardly pointed nose on said pawl adapted to fall above the top edge of the standard when the lifting bar has been raised by the lever a designated distance, to hold the latter in an elevated 125 position.

4. In a jack, the combination with a tubular standard, of a lifting bar slidably movable therein, a lever for raising said lifting bar, an adjustable collar on said lifting bar, 130

having two outwardly extending ears, a bolt extending between said ears, a nut on said bolt, a pawl pivotally mounted on said bolt above the standard, and a downwardly pointed nose on said pawl adapted to fall above the top edge of the standard when the lifting bar has been raised by the lever a designated distance, said lever having a hole provided in its outer end to fit said nut for

the purpose of vertically adjusting said collar on the lifting bar to accommodate different height machines.

In testimony whereof I have hereunto set my hand this 8th day of August, 1917.

ALEXANDER W. MARR.
